UNITED STATES PATENT OFFICE

158,852

CLOCKCASE

Hervé H. Goldner, New York, N. Y.

Application December 27, 1949, Serial No. 6,843

Term of patent 14 years

(Cl. D42—7)

To all whom it may concern:

Be it known that I, Hervé H. Goldner, a citizen of the United States, residing at New York city, in the county and State of New York, have invented a new, original, and ornamental Design for a Clockcase, of which the following is a specification, reference being had to the accompanying drawing, forming a part thereof.

Fig. 1 is a top plan view of a clockcase, showing my new design.

Fig. 2 is a front elevation thereof.

I claim:

The ornamental design for a clockcase, substantially as shown.

HERVÉ H. GOLDNER.
